JAMES L. MITCHAM AND JAMES W. BURNS, OF ROCKDALE, TEXAS.

SCOOP.

1,313,408.

Specification of Letters Patent.

Patented Aug. 19, 1919.

Application filed February 28, 1918. Serial No. 219,726.

To all whom it may concern:

Be it known that we, JAMES L. MITCHAM and JAMES W. BURNS, citizens of the United States, residing at Rockdale, in the county 5 of Milam and State of Texas, have invented certain new and useful Improvements in Scoops, of which the following is a specification.

This invention relates to scoops, and more 10 particularly to a scoop of the wheel type.

One of the main objects of the invention is to provide a scoop of the character stated of simple construction and operation which may be produced at comparatively small 15 cost. A further object is to provide a scoop rockably mounted on a supporting axle and securely braced thereto so as to prevent any looseness or play of the scoop proper. A further object is to provide an operating 20 handle for tilting and lifting the scoop which extends the full width thereof, this handle being so associated with a foot rest as to provide a gripping rod when the operator is standing upon the rest. Further 25 objects will appear from the detailed description.

In the drawings:

Figure 1 is a side view of a scoop constructed in accordance with our invention, 30 Fig. 2 is a top plan view,

Fig. 3 is a front elevation.

The scoop body or shovel 1 may be of any suitable or well known construction. This body is suspended from and rockably 35 mounted on the central dropped portion 2 of the supporting cranked axle, at each end of which is a spindle carrying a ground wheel 4. Brace rods 5 are secured at their forward ends to the side walls 6 of the 40 scoop shovel 1 and have their upper ends secured about the spindles 3. These rods serve to maintain the scoop 1 in proper relation to the central dropped portion 2 of the axle and, being positioned adjacent 45 the vertical arms 7 of the axle, serve to brace the scoop against lateral movement.

An upwardly and rearwardly inclined arm 8 is secured to each side wall 6 of the shovel adjacent the rearward end thereof. 50 A hand rod 9 is secured between the upper

ends of arms 8, and coöperates therewith to form a handle for tilting the shovel 1 about the axle. An angular foot rest 10 is secured to the back wall 11 of the shovel at the transverse center thereof. This foot rest is so positioned that when the operator is standing thereon he can readily grasp the hand rod 9 so as to hold himself in position while the scoop is being drawn to the place at which it is desired to discharge the material therein, the weight of the operator thus counterbalancing the material contained within the shovel 1 in advance of the axle 3 so as to prevent forward and downward tipping of the scoop. 60

As will be noted more particularly from Fig. 1 of the drawings, scoop shovel 1 projects farther in front of the axle 3 than in the rear thereof. For this reason there is a tendency for the scoop to rock downward 70 and forward about the dropped center 2 so as to bring the forward edge thereof into engagement with the ground surface. This tendency is overcome by the operator who throws his weight on the foot rest, and when it is desired to empty the scoop, it is only necessary for the operator to step off of the foot rest 10 permitting the front edge of the scoop to engage the ground surface, and as the scoop is drawn forwardly, the shovel 80 1 will be rocked about the bar 2 lifting the axle and the wheels carried thereby from the ground and discharging the contents of the shovel. By constructing the scoop in this manner, the operator may ride upon 85 the scoop when carrying a load and, by the simple expedient of stepping off of the foot rest 10, the scoop will be automatically dumped. This scoop is of extremely simple construction and may, therefore be produced at comparatively small cost. 90

What we claim is:

In a scoop, the combination with an axle having a dropped center and spindles at its extremities supported by ground wheels; of 95 a scoop shovel disposed wholly below the line of the spindles and having its side walls hung on the dropped portion of the axle, its front edge being positioned to travel just above the surface of the earth and nor- 100

mally engaging the same by preponderance of weight, a handle upstanding from the rear end of the scoop, braces from the side walls to the handle and to said spindles, and 5 a foot rest on said rear end whereby the operator may place his weight thereon and raise the front edge of the scoop, for the purpose set forth.

In testimony whereof we affix our signatures in presence of two witnesses.

JAMES L. MITCHAM.
JAMES W. BURNS.

Witnesses:

A. A. OFFIELD,
JNO. L. WARD.
